PLAY PEN AND WALKING DEVICE

George B. Wisecarver, Columbus, Ohio

Application May 31, 1939, Serial No. 276,703

3 Claims. (Cl. 155—22)

The present invention relates to a new and improved play pen and walking device especially adapted for enabling a baby to walk without the aid of human assistance.

5 An important object of the invention resides in the provision of a combination play pen and walking device that will serve to restrict the activities of the baby placed therein while precluding the possibility of self-sustained injury.

10 A further object of the invention is to provide a combination play pen and walking device comprising a hollow elastic top ring supported upon leg members which extend through the lower side of the ring and are secured to the upper side thereof.

15 The leg members are mounted upon casters which render the device readily transportable, and as additional confining means there are provided annular rubber members supported in spaced relation on the leg members between the top ring and the casters. A guard member is disposed substantially centrally of the top ring being adapted to prevent injury to the child's fingers by being caught between the top ring and a door frame or article of furniture.

20 The invention will be fully and comprehensively understood from a consideration of the following detailed description when read in connection with the accompanying drawing which 30 forms a part of the application.

In the drawing:

Figure 1 is a top plan view of the device.

Figure 2 is a side elevational view thereof, and

35 Figure 3 is a detail sectional view through the top ring and illustrating the manner of attaching the leg members thereto.

40 Referring to the drawing for a more detailed description thereof, the combination play pen and walking device indicated generally by the reference numeral 5 comprises a top ring 6 formed of rubber or other elastic material, the same being hollow and open at its inner side, as more clearly shown in Figure 3 of the drawing. The ring 6 is of substantially the same 45 shape and construction as a pneumatic tire comprising upper and lower side walls 7 and 8, respectively, and front wall 9. The flanged portions 10 formed on the open inner side wall serve as gripping members for the child confined within 50 the ring and may be engaged when moving the device over the floor while learning to walk. The interior of the ring 6 being hollow may further serve as a receptacle for containing various articles such as toys and the like.

55 The front wall 9 of the ring 6 is preferably

formed with a hollow substantially cylindrical-shaped guard ring 11 of rubber or the like which may be vulcanized or otherwise secured thereto. The purpose of the guard ring 11 is to protect the hands or fingers of the infant from coming in contact with a door frame, wall or article of furniture within the room as the device is moved by the walking motion of the user. The guard ring 11 may be removably attached to the ring 6 in which case it would be attached to said ring by means of a clamp or the like 12 as shown in Figure 2 of the drawing.

5 The ring 6 is mounted in a horizontal position on leg members 13, said members being of any desired shape or size and arranged in spaced relation relative to the ring. Each leg member 13 extends through a slotted opening 14 formed in the lower side wall 8 of the ring, the extending or upper end of the leg abutting the inner portion of the side wall 7, being held thereto by 10 means of a screw or the like 15 and washer 16. The leg members will be rigidly held within the opening 14 by means of the screw 15 thereby 15 eliminating the use of the conventional rungs.

To serve as an additional means of confining the infant within the device, there is provided a series of rubber or the like rings 17 attached to each of the leg members by means of a bracket 18. The rubber rings 17 are preferably sufficiently rigid to support the weight of the infant 20 or child when raising himself from a sitting or kneeling position to a standing position.

25 The leg members 13 are supported on conventional casters 19, each caster being provided with a semi-circular shaped guard 20 to prevent 30 contact of the infant therewith. The guards 20 are attached to the lower ends of the leg members 13 by screws or other fastening means 21.

The herein described and illustrated play pen and walking device has been constructed in a 35 manner to afford healthful and amusing exercise to the user. As the infant progresses in size and strength and is able to assume a standing position, the device renders a natural aid in enabling the infant to acquire the steps necessary to walk. 40 By reason of the fact that the device is primarily constructed of a rubber-like material, there will be precluded the possibility of the marring of furniture as the device is moved over the floor.

45 Also it will be understood, of course, by those skilled in the art that variations in the hereinabove described device involving the substitution of substantial equivalents for the devices described are intended to be comprehended within 50 the spirit of the present invention and that the 55

invention is capable of extended application and is not confined to the exact showing of the drawing nor to the precise construction described and, therefore, such changes and modifications may 5 be made therein as do not affect the spirit of the invention nor exceed the scope thereof as expressed in the appended claims.

What is claimed is:

1. A device of the character described comprising, 10 a substantially hollow rubber-like ring, supporting means extending through one wall of said ring and attached to the opposite wall, a guard ring secured to the outer side of said ring, and means attached to said supporting means for 15 rendering said device portable.
2. A device of the character described comprising, a hollow substantially cylindrical-shaped rubber ring, the inner side of said ring being open, leg members for said ring, said leg mem-

bers extending through an opening formed in the lower side of said ring and abutting the inner portion of the upper side thereof, means for attaching said leg members to the upper side of said ring, and guard means secured to said 5 ring.

3. A play pen and walking device of the character described comprising, an enclosing ring, said ring being formed of an elastic material and of hollow construction, supporting means for said 10 ring, said means including vertically disposed leg members extending through one wall of said ring with means projecting from the upper end of said leg members and extending through the opposite wall of said ring for attachment thereto, and guard means secured to the outer portion of 15 said ring.
